UNITED STATES PATENT OFFICE.

ELGIN C. HARTSHORN, OF DENVER, COLORADO.

FOLDING SOFA-BED.

SPECIFICATION forming part of Letters Patent No. 700,042, dated May 13, 1902.

Application filed April 9, 1901. Serial No. 55,056. (No model.)

To all whom it may concern:

Be it known that I, ELGIN C. HARTSHORN, a citizen of the United States, residing at Denver, in the county of Arapahoe and State of Colorado, have invented certain new and useful Improvements in Folding Sofa-Beds; and I declare the following to be a full, clear, and exact description of my invention, such as will enable others skilled in the art to which it appertains to make and use the same, reference being had to the accompanying drawings, forming a part of this specification, in which similar letters of reference indicate corresponding parts in all the figures.

15 My invention relates to a class of sofas adapted to be unfolded or spread out, forming a full-sized bed.

The objects of my invention are to provide certain improvements in folding sofa-beds 20 provided with removable ends, such improvements relating, first, to the connecting devices by which the seat is secured detachably to the ends, and, second, to the hinging of the seat and back. Regarding the connections 25 between the seat and the ends, it is especially important in an article of this character to employ connections which will not be materially affected by dampness or heat, since the frame of the seat and the ends being made 30 of wood they are readily susceptible to the influence of heat or moisture, and unless the connecting devices are so constructed as not to be carried out of adjustment thereby they are apt to bind or to fail to fit, preventing 35 the putting together or separation of the parts of the sofa. Furthermore, owing to the nature of the uses to which sofa-beds are put it is of great importance that the seat be provided with a broad or extended support on 40 the ends. A construction which answers these requirements is one of the principal features of my present invention. Regarding the hinge connections of the back and seat in sofa-beds, it is highly desirable to provide 45 ample space for springs without interfering with the swinging up of the seat to expose the wardrobe-space beneath it, as well when the back is in its vertical position as when it is turned down to form a bed. This also is 50 provided for by my invention.

I attain the above objects by the construction outlined in the drawings, in which—

Figure 1 is an end view of my new folding sofa-bed having the end removed, showing the manner in which the seat and the back 55 are hinged together. Fig. 2 is an end view showing the back lowered to the position it occupies when forming a full-sized bed. Fig. 3 is an isometrical view representing the device in sofa form. Fig. 4 is a front view having a 60 section of the box-front removed, showing the end fastening device. Fig. 5 is a perspective end view having the end removed. Fig. 6 is an elevation of the end showing the fastening device. 65

A represents the seat of the sofa. B represents the back of same.

C represents a supporting post or beam which is constructed of wood or other suitable material, to which are hinged the seat 70 and the back of the sofa by means of the hinges, (designated by C' and C².) As best shown in Figs. 1 and 2, the seat A and back B are box-shaped, being, in fact, composed of boxes in which the springs are carried, and 75 they are hinged by the hinges C' C², placed at or near their upper inner edges to opposite sides of the posts or beams C, so that the hinges are spaced a distance apart. This construction is an important part of my invention, since 80 by it I provide for using the springs necessary to a satisfactory sofa-bed without interfering with the swinging of the seat or back, the seat being freely movable upward when the back is upright as well as when it is 85 turned down. It is thus possible to provide a wardrobe or clothes-chest under the seat, notwithstanding the fact that the seat is practically a regular box-spring. The ends of the sofa represented by C³ and C⁴ are provided 90 with swinging portions, (indicated by C⁵ and C⁶.) These parts C⁵ and C⁶ are hinged to the ends of the sofa and are provided with cleats similar to the one designated by C⁷, which are adapted to form a support for the back 95 of the sofa when it is lowered to form a bed. Suitable beveled devices on the principle of the one designated by C⁸ in Fig. 6 of the drawings are provided on the inner lower side of the ends of the sofa. These beveled 100

devices are adapted to wedge into a beveled surface provided on the cross-pieces represented by C¹⁰ and C¹¹ and forming part of the box construction. These devices—namely, 5 the beveled contrivances attached to the ends and the cross-pieces designated by C¹⁰ and C¹¹—are in the form of male and female members and have oppositely-inclined surfaces adapted to wedge tightly together, as fully illustrated in Fig. 4 of the drawings. This construction is one of the most essential features of my invention, as it provides a fastening device for the ends of the sofa which securely and rigidly holds the ends, although 10 so constructed that they can very readily be removed to facilitate the undoing of the sofa-bed when desiring to pack it for shipping or for placing it into a knocked-down condition, facilitating the ingress and egress into buildings, &c. It further provides an extended or broad bearing for the seat and accommodates itself to variations caused by swelling or shrinking of the wood of which the parts of the sofa-bed are composed, so that there is 15 never any difficulty about the assembling or separation of the parts, which adjust themselves to each other automatically. The swinging or hinged parts, of the ends can be swung outward into the position occupied in 20 Fig. 2 of the drawings and the back lowered to the position occupied in said figure when it rests upon the cleats or supports designated by C⁷, as fully illustrated in Fig. 2. Any suitable contrivance may be utilized to 25 hold the swinging parts of the ends against the back of the sofa when it is raised to the upright position. (Shown in Figs. 1, 3, and 5 of the drawings.) In the drawings I have shown thumb-latches C⁸ for this purpose. Said 30 thumb-latches are pivoted near the ends of the back B and are adapted to engage the upper edges of the hinged parts C⁵ C⁶ when they are in the position shown in Figs. 1, 3, 4, and 5. 35 After a folding sofa-bed has been constructed 40 according to the foregoing description and the different illustrations in the drawings the operation of same is very simple. When desiring to produce a bed, the swinging parts C⁵ and C⁶ of the ends C³ and C⁴ are swung 45 outward, as illustrated in Fig. 2 of the drawings. The back is lowered to the position represented in said figure and rests upon the cleats indicated by C⁷. When desiring to remove the ends for purposes hereinbefore referred to, the simple operation of striking on 50 the top of the end parts will loosen the beveled fastening device formed by the beveled contrivance of the principle indicated by C⁹ and the cross-pieces designated by C¹⁰ and C¹¹. 55 After having thus described the nature and objects of my invention, with the manner of constructing and operating the same, what I claim as new, and desire to secure by Letters 60 Patent, is—

65 1. In a sofa-bed, the combination with a pair of ends, each composed of a stationary

and an adjustable section hinged together whereby the said adjustable section may be extended in alinement with the stationary section and arranged at right angles to said stationary section, of a vertically-extending support arranged between the stationary section of the ends, an adjustable seat adapted to engage over and upon the top of said support when the said seat is in a lowered position, means for suitably hinging one side of the seat to the support to permit of elevating the said seat, an adjustable back adapted to extend over and upon the top of the said support when the said back is in a lowered position, means for suitably hinging the back to the said support to permit of vertically adjusting the said back, an elongated cleat secured to the stationary sections of the ends, cleats connected to the seat and engaging in the cleats of the ends for supporting the seat when in a lowered position, and means carried by the adjustable sections of the ends for supporting the back when in a lowered position.

2. In a sofa-bed, the combination with a pair of ends, each composed of a stationary and an adjustable section hinged together whereby the said adjustable section may be extended in alinement with the stationary section and arranged at right angles to said stationary section, of a vertically-extending support arranged between the stationary section of the ends, an adjustable seat adapted to engage over and upon the top of said support when the said seat is in a lowered position, means for suitably hinging one side of the seat to the support to permit of elevating the said seat, an adjustable back adapted to extend over and upon the top of the said support when the said back is in a lowered position, means for suitably hinging the back to the said support to permit of vertically adjusting the said back, an elongated cleat secured to the stationary sections of the ends, 95 cleats connected to the seat and engaging in the cleats of the ends for supporting the seat when in a lowered position, and means carried by the adjustable sections of the ends for supporting the back when in a lowered position.

3. In a sofa-bed, the combination with a pair of ends each composed of a stationary and an adjustable section hinged together 100 whereby the adjustable section may be extended in alinement with the stationary section, a support arranged between the sections, a seat, means for hinging the seat to the said support, an adjustable back, means for hinging the back to the support, means carried by the ends and engaging with the seat for 105

supporting the same, means carried by the adjustable sections for supporting the back when in a lowered position, and means carried by the rear face of the back and adapted to engage with the top of the adjustable sections of the ends for securing the back in a vertical position.

In testimony that I claim the foregoing as my own I hereunto subscribe my name in the presence of two witnesses.

ELGIN C. HARTSHORN.
